UNITED STATES PATENT OFFICE

99,275

DESIGN FOR A MERCHANTISE DISPLAY CABINET

Charles Fleischer, New York, N. Y.

Application January 22, 1936, Serial No. 60,731

Term of patent 3½ years

To all whom it may concern:

Be it known that I, Charles Fleischer, a citizen of the United States, residing at New York, N. Y., have invented a new, original, and ornamental Design for a Merchandise Display Cabinet, of which the following is a specification, reference being had to the accompanying drawing forming part thereof.

Fig. 1 is a front elevational view of a merchandise display cabinet, showing my new design, and Fig. 2 is a section, in plan, taken on the line 2—2 of Fig. 1.

I claim:

The ornamental design for a merchandise display cabinet as shown.

In testimony whereof, I affix my signature.

CHARLES FLEISCHER.
